INVENTOR

G. Everett Hill.

UNITED STATES PATENT OFFICE.

G. EVERETT HILL, OF PHILADELPHIA, PENNSYLVANIA.

CASTER.

SPECIFICATION forming part of Letters Patent No. 363,637, dated May 24, 1887.

Application filed December 6, 1886. Serial No. 220,786. (No model.)

To all whom it may concern:

Be it known that I, G. EVERETT HILL, a citizen of the United States, residing in the city of Philadelphia, State of Pennsylvania, 5 have invented a new and useful Improvement in Casters, of which invention the following is a specification.

The object of this invention is to make the 10 caster adjustable as to height, so that it can offer a firm and equal support where floors sag or are off of level, or where the legs of furniture are of unequal length.

It consists of three pieces—viz., first, a socket 15 set more or less into the article of furniture and provided with an internal screw-thread; second, a plug attached to the vertical spindle of the caster and provided with a screw-thread corresponding with that on the socket, and, third, a set-screw by which these two parts are 20 held in position after adjustment.

In the annexed drawings, Figure 1 shows an elevation of a caster embodying my invention and applied to a furniture-leg, shown in section; Fig. 2, a similar view showing a modification in the exterior form of the socket; Fig. 25 3, a vertical section on a middle line through Fig. 1.

a represents a leg of any article of furniture; *b*, a metallic socket set in a recess in leg *a*, and 30 secured in position by means of a screw, *c*, or other equivalent fastening. The socket *b* is provided with the internal screw-thread, *d*, which extends the whole depth of the socket. *e* is the vertical spindle of the caster. *f* is a 35 plug provided with the exterior screw-thread, *g*, corresponding with the screw-thread *d* and with the flange *g'*, which overlaps the socket *b*. The edge of this flange is milled, to facilitate 40 adjustment by rotation. The spindle *e* is riveted at *h*, to attach it to the plug *f*. *i* is a set-screw. When the legs of furniture to 45 which these casters are applied are found to bear unevenly on the floor, the plug *f* is adjusted up or down by application of the thumb

and finger to the milled edge of the flange *g'* to counteract the unevenness, and the set-screw *i* then tightened to hold the adjustment.

There is a class of casters which are made adjustable by means of a screw-thread on the spindle. As this spindle is necessarily slender, any lateral strain caused by rolling or moving the furniture tends to break or bend the spindle, and thus destroy the usefulness of the 50 caster. The diameter of plug *f*, which in my caster carries the screw-thread, is sufficient to afford all necessary strength. In another class of adjustable casters the weight of the furniture comes on a washer or a thin face-plate applied to the end of the furniture-leg. Owing to the thinness of such devices they can contain but few screw-threads, affording a less secure bearing than the socket *b* and plug *f* of my 55 caster.

It will be seen that my caster possesses a much greater capability of resistance to both 60 lateral and vertical strains.

In Fig. 2 the socket *b* is shown provided with a shoulder, *b'*, the interior construction being similar to that shown in Fig. 3. A 65 socket of this form is better adapted in cases 70 where the wood is soft or the leg small.

I claim—

In combination with the vertical spindle of a 75 caster, the socket *b*, provided with secure means for attaching it to the furniture-leg and with an internal screw-thread extending its entire depth, the plug *f*, provided with an external screw-thread extending its whole length in correspondence with that of the socket *b*, and provided further with a projecting flange 80 having a milled edge, and the set-screw *i*, all for the purpose of making a durable caster vertically adjustable, substantially as set forth.

G. EVERETT HILL.
